LINE DRAWING DEVICE

José Gutiérrez Pérez, Buenos Aires, Argentina,
assignor of one-fifth to Isidro Satanowsky and
one-fifth to Manuel Augusto Marques de Silva,
Buenos Aires, Argentina

Application April 9, 1946, Serial No. 660,713

2 Claims. (Cl. 197—113)

1

The present invention relates to a line drawing device suitable for use on typewriters, calculating machines and the like, and has for its object to provide an auxiliary element or accessory which, by the manner in which it acts mechanically in mounted position serves almost as an additional type element for tabulating and making all kinds of lines, both horizontally and vertically.

Typewriters and other hand-operated typing machines, have latterly been improved from every point of view, but all of them ignore the question of drawing lines which are so frequently necessary in different classes of work as to become a practical want, felt by the operator in general, who must rely upon improvisations which are a burden owing to the loss of time implied by their execution.

For these reasons, a device especially designed to meet this want and having all the necessary means for putting it immediately into service such as, in fact, the present invention concerns, may be classified as a necessary adjunct to complete the components of manual typing machines or apparatus.

The line drawing device of the present invention consists in a carrier for writing instruments which by means of a support is mounted in a convenient position on the machine so as to have the writing point directed towards the roller, but without being in permanent engagement therewith, since to this end it is movably mounted on the support and is provided with actuating means which may readily be operated to bring the device into writing or marking position.

In addition to the foregoing, the present invention contemplates various objects, amongst which may be pointed out the possibility of bringing the line drawing device into play without interrupting the typing for a time longer than that strictly necessary for the operation.

Another object of the invention is to obtain clean lines both horizontally and vertically, since in addition to a retraction mechanism, the mounting comprises a resilient system which maintains the pressure necessary to ensure engagement of the paper, or other writing surface provided in the machine.

A further object is to enable any kind of writing instrument to be used in the device, whether such instrument be specially designed for the apparatus or of the so-called pocket variety, since in addition to the mounting, the line drawing device comprises pencil or pen holders.

Other objects of the present invention will become apparent in the course of the detailed description thereof which for greater clarity and readier understanding has been illustrated by various figures in which the line drawing device

2

has been shown in a preferred embodiment, by way of example.

In the drawings:

Fig. 1 is a longitudinal section of the device shown in operative position, that is to say that the point of the writing instrument is in contact with the paper supported on the roller of the manual typing machine or apparatus.

Fig. 2 is a view of the same assembly as shown in Fig. 1, but in inoperative position, that is to say with the writing instrument retracted so as to leave the space free for continued operation of the type bars of the machine.

Fig. 3 is a view of the device after being rotated through 90° with respect to the assembly shown in previous Fig. 2; in this figure, by means of a partial section, we have shown the cam governing the retraction of the writing instrument, and finally,

Fig. 4 is a perspective view of the device applied to a typewriter the paper of which, located on the roller of the carriage, has been tabulated with horizontal and vertical lines drawn by the aforesaid device.

In the several figures the same reference numerals indicate like or corresponding parts or elements. Devices or elements comprising several parts are indicated by reference letters.

As may be seen in the drawings, *a* is the support which has a housing *1* through the bore of which is fitted the movable element *b*. Said movable element *b* comprises a carrier *2* which is tubular and has a frusto-conical end *2'* in which fits the frusto-conical portion of the writing instrument *3*, which is accommodated in the hollow of the carrier *2*. The frusto-conical end *2'* terminates in an aperture *2''* through which projects the writing point *3'* which may be that of a pen or a pencil. The writing instrument *3* is secured by the gripping action of the tongues formed by cuts *4* in the screw-threaded portion *5*. On said screw-threaded portion *5*, is a nut *6* which is somewhat conical so that as it moves forward along the thread of the portion *5*, it may exert progressively compressive action in order to create the grip which holds the writing instrument *3* in position.

The carrier *2* has an annular projection *7* against which the spring *8* bears, which spring surrounds the carrier *2* and is enclosed in the housing *1*, and bears on the seat *9* formed in said housing. Under the pressure of said spring *8*, the movable element *b* tends to advance and occupy the operative position shown in Figs. 1 and 4.

The movable element *b* includes a hood *10* which is intimately united to the carrier *2* and the bore of said hood is such that it can slide telescopically over the surface of the housing *1* of the support *a*. The hood *10* of the device *b*

has internally a cam 11 the pin 12 of which is rotatably fitted in a hole 13, through which said pin 12 extends outside the hood 10 where it terminates in an operative knob 14. By a hand actuation of said knob the cam may be brought into one of two positions, one of which is shown in Fig. 1, and the other of which is shown in Figs. 2 and 3.

The position of Fig. 1 is that corresponding to the inoperative position of the cam, which then lies in a transverse direction with its smallest dimensions lying between the hood and the housing, so that it does not prevent the spring 8 from displacing the device b towards the operative position thereof, that it to say, so that the writing point 3' engages the paper 15 disposed on the roller 16 of the manual typing machine or apparatus c on which the line drawing device is mounted.

The position of Figs. 2 and 3 is that in which the retraction has been effected, since the cam 11 by interposing its major dimension between the hood and the housing 1 of the support a forces the movable member b backwards sufficiently to retract the point 3' from the paper 15 and permit the operator to continue writing thereon as usual in manual typing apparatus.

Since the support a is fixed to any portion of the manual typing machine or apparatus, as shown in Fig. 4, it is sufficient to bring the cam 11 into the position of Fig. 1 in order that the spring 8 may displace the movable member b until the writing point 3' of the member 2 engages the paper 15 disposed on the roller 16 of the carriage of the machine c. This same spring serves also to provide the pressure necessary in order that the contact of the writing point 3' with the paper shall be effective and of such value that when the carriage c' is moved, horizontal lines are traced and when the roller 16 is turned, vertical lines are marked on the paper 15.

To retract and put out of action the element b, all that is requisite is to operate the knob 14 so as to bring it from the position of Fig. 1 into the position of Figs. 2 and 3, since in this manner the cam 11 is interposed in the space inside the hood 10, and bearing on the housing 1 causes the said device b to be retracted sufficiently to separate the point 3' from the paper 15.

The device described may remain permanently mounted on the machine without in any way interfering with the typing, but to this end it should preferably be disposed in front, in the manner of a bridge, as shown in Fig. 4, out of the way of the path of movement of the type fingers which respond to the keys of the machine c.

While the device is in inoperative position, Figs. 2 and 3, the spring 8 is under its full load, so that at the time when it is desired to use the instrument in order to draw lines, whether horizontal or vertical, it may be brought into operative position practically instantaneously, since it responds immediately to manual actuation of the knob 14 to bring the cam 11 into the position of Fig. 1, and release the element b so that the spring pressure may urge the writing point 3' into engagement with the paper 15.

It will be clear to those skilled in the art that in carrying the invention into practice we may introduce sundry modifications as regards the construction and form of the device described, without thereby departing from the fundamental

principles which are clearly set forth in the accompanying claims.

I claim:

1. A line drawing device for typewriters, calculating machines and the like, which comprises a support adapted to be fixed to the machine and including a housing having a bore, a movable member consisting in a tubular body having a frusto-conical forward end and an externally screw-threaded rearward end divided into a plurality of flexible tongues by longitudinal cuts, a writing instrument extending inside said movable member through substantially the entire length thereof and having a writing point projecting beyond said forward end of the movable member, a nut on said rearward end having an internally threaded frusto-conical portion engaging said external screw thread to cause said tongues to grip said writing instrument, said movable member being slidably mounted in the bore of the housing with said writing point directed towards a portion of the machine where a writing surface is supported, spring means in said housing and around the movable member and arranged to normally urge the movable member towards said writing surface to engage the same under line marking pressure and retraction means for the movable member including cam means interposed between said movable member and said housing normally urge the movable member towards said writing surface to engage the same under line marking pressure and retraction means for the movable member including cam means interposed between said movable member and said housing and movable between an inoperative position and an operative position in which the cam acts to oppose the spring and retract the movable member from engagement with said writing surface.

2. A line drawing device for typewriters, calculating machines and the like, which comprises a support adapted to be fixed to the machine and including a housing having a bore, a movable member including a holder for a writing instrument, said holder being slidably mounted in said bore, a writing instrument carried by said holder, spring means in said housing surrounding the movable member and arranged to normally urge said movable member towards an operative position in which the writing point of the writing instrument is in contact with a writing surface provided in the machine, and retraction means for the movable member including cam means movable between an inoperative position and an operative position in which the cam acts to oppose the spring and retract the movable member from engagement with the writing surface, said retraction means including a hood member fixedly secured to the movable member and extending over said housing, the cam means being disposed within said hood member and between the same and a portion of the housing remote from the writing surface.
